UNITED STATES PATENT OFFICE.

JOHN BARTA, OF CHICAGO, ILLINOIS.

CRADLE.

SPECIFICATION forming part of Letters Patent No. 744,993, dated November 24, 1903.

Application filed August 22, 1903. Serial No. 170,432. (No model.)

To all whom it may concern:

Be it known that I, JOHN BARTA, a citizen of the United States, residing at Chicago, in the county of Cook and State of Illinois, have invented a new and useful Cradle, of which the following is a specification.

My invention is a combined cradle and bed; and the object of my invention is to provide a cradle with a projecting hood at the head 10 and to provide means whereby without the use of tools or additional parts the said cradle may be converted into a child's bed with rollers thereon.

My invention consists in a cradle having a 15 hinged end and hood at the head which can be swung downward, the end of the cradle forming when in a horizontal position an extension of the bottom and the hood becoming the head of the bed.

20 My invention also comprises rollers carried by the ends of the rockers and adapted to be turned downward and locked in a vertical position.

25 My invention further comprises the novel features of construction and combination of parts hereinafter described, particularly pointed out in the claims, and shown in the accompanying drawings, in which—

Figure 1 is a perspective view of my cradle. 30 Fig. 2 is a side elevation of same converted into a bed. Fig. 3 is an elevation of one of the supporting-legs, showing the manner of connecting the rocker and the caster to the same. Fig. 4 is a similar view, the leg being 35 turned to a vertical position. Fig. 5 is a plan view of an end portion of a rocker with the caster in a horizontal or inoperative position.

In constructing my cradle I employ a body A, of wood or metal and of any preferred 40 design. The head end of this body comprises a rectangular frame A', having angled vertical side members which are pivoted at their lower ends to the ends of the side members A² of the body portion. This end frame supports a hood A³, which normally extends over the head end of the body portion of the cradle, and has the side frames A⁴. These side frames comprise bars or members A⁵, angled throughout a portion of their length, the lower 45 ends of the angled portions resting when the hood is in its normal position on the upper side bars A⁶ of the body and acting both as

a support for the hood and as a stop to limit inward swinging movement of the end frame A'. On each side of the body is arranged a 55 pin A⁷, which is engaged by a catch A⁸, pivoted to the end frame and having a plurality of notches therein adapted to fit over the pin A⁷.

When formed of metal, I prefer to have the 60 corner-pieces B of the body portion angled, and these extend downward below the body portion, forming the supporting-legs. The lower ends B' of these supporting-legs are bent inward and the rocker C, formed of a 65 broad curved plate, is riveted to the inward bent portion B'. The end portion of each rocker is reduced in width, being cut out along the inner side, as shown at C². A plate C³ is carried by each end of each rocker, being interposed between the rocker and the end B', and adjacent the legs B the plates are crimped, and pivot-pins C⁴ are carried by the crimped portions, the said pins being arranged at a right angle to the rocker and extending 70 into the cut-out portions C². The supplemental supporting-legs D are each bent upon themselves at their lower ends to form sockets D' for the shanks of the usual caster-brackets carrying the rollers D². Each of the supplemental legs D is cut out or reduced in width 75 in its upper portion, whereby it is adapted to fit into the cut-out portion C² of the rocker. Each leg D has secured to it a plate D³, crimped to register with the crimped portion 80 of one of the plates C³, and in the crimped portion of the plate D³ is journaled one end of one of the pivot-pins C⁴. It is obvious, therefore, that the leg D can be swung into alignment with the rocker to which it is pivoted, or 85 it may be swung downward parallel to the supporting-leg B, forming virtually an extension of the same.

To lock the adjustable supplemental legs D in the desired position, plates E are pivoted 90 to the legs B and at their lower ends are curved to form foot portions E'. Each plate E has a lug E² extending from one side and which is bent back on the plate, forming a hook. When the leg D is in a non-operative 95 position, the foot of the plate E bears on the plate D³ to the rear of the pivotal point. To turn the leg D into a vertical position, the plate E is turned up, lifting the foot from the 100

plate D³, and the leg D is swung into operative or vertical position. The plate E is then turned back to its normal position, and the hook formed by the lug E² engages the 5 upper portion of the leg D and holds it in a vertical position.

To convert the cradle into a child's bed, it is only necessary to lift the catches A⁸ and swing the end frame A' to a horizontal position, locking it in that position by again engaging the pins A⁷ with the catches A⁸. The hood A³ then becomes the head of the bed.

On the forward part of the hood are arranged brackets F, carrying between them a bar F', to which a netting may be secured to 15 protect the child from flies.

It will be obvious that where the rockers and supporting-legs are formed of wood instead of metal many changes in minor details 20 would be required in view of the change of material, the bent pieces B' being dispensed with and the sockets for the casters being formed in the usual manner. These departures from the details of construction shown 25 and described do not, however, effect the merits of my invention or depart from the scope of same.

Having thus fully described my invention, what I claim as new, and desire to secure by 30 Letters Patent, is—

1. The combination with a cradle-body, of a pivoted end piece extending vertically above the sides, means for locking said end piece in a vertical position, a frame forming a hood 35 carried by the end piece and extending over the body of the cradle, side members connected to said hood and adapted to rest on the sides of said cradle-body when the end piece is in a vertical position, and means for locking 40 the end piece in a horizontal position, whereby the end piece becomes an extension of the cradle-bottom and the hood becomes the end piece of said extension.

2. The combination with a body portion of 45 a cradle, of the rectangular, pivoted frame A', carrying at one end the frame A³, arranged

at a right angle to the frame A', the said frame A', being adapted when swung into a vertical position to form an end piece of the body portion and when swung in a horizontal position, 50 to form an extension of the bottom of the body portion, the frame A³, being adapted to form a hood when the frame A', is in a vertical position and to form an end piece when the frame A', is in a horizontal position, a pin 55 carried by the body portion, and a catch carried by the frame A', and adapted to engage the pin when the frame A', is in a vertical or horizontal position.

3. A convertible cradle comprising a body 60 portion and rockers, an adjustable end piece adapted to swing downward and extend the length of the body portion, and supplemental roller-carrying legs adapted to form an extension of the rockers and to be swung downward below the rockers into a vertical position.

4. A combined cradle and child's bed comprising a body portion having supporting-legs, rockers secured to the lower ends of said legs, a swinging frame, pivoted at one end of the 70 body portion and adapted to form an end piece when adjusted in a vertical position and to form an extension of the body portion when adjusted in a horizontal position, supplemental legs pivoted to the ends of the rockers and 75 adapted to be swung into alinement with said rockers or to be adjusted parallel to the supporting-legs of the body portion, and rollers carried by the supplemental legs.

5. The combination with an extensible 80 cradle of the kind described, rockers carried by said cradle, said rockers being reduced in width adjacent their ends, pivot-pins carried by said reduced portions, adjustable supplemental legs reduced in their upper portions 85 and journaled on said pivot-pins, rollers carried by said supplemental legs, and means for locking the said legs in the desired position.

JOHN BARTA.
